Primary Examiner — Kimberly Barnes*Assistant Examiner* — Sarah A Nguyen(74) *Attorney, Agent, or Firm* — BERESKIN & PARR LLP/S.E.N.C.R.L., s.r.l.(57) **CLAIM**

I claim the ornamental design for a steam mop, as shown and described.

DESCRIPTION

FIG. 1 is a front perspective view of a steam mop showing my new design;

FIG. 2 is a left side view of the steam mop of FIG. 1;

FIG. 3 is a front view of the steam mop of FIG. 1;

FIG. 4 is a right side view of the steam mop of FIG. 1;

FIG. 5 is a rear view of the steam mop of FIG. 1;

FIG. 6 is a top view of the steam mop of FIG. 1; and,

FIG. 7 is a bottom view of the steam mop of FIG. 1.

The broken lines in the drawings depict portions of the steam mop that form no part of the claimed design.
